UNITED STATES PATENT OFFICE.

HENRY GOODWIN HOORNBEEK, OF SPRINGFIELD, MASSACHUSETTS, ASSIGNOR TO
WESTERN ELECTRIC COMPANY, INCORPORATED, OF NEW YORK, N. Y., A COR-
PORATION OF NEW YORK.

STRAND-WORKING MACHINE.

Application filed December 11, 1923. Serial No. 680,023.

To all whom it may concern:

Be it known that I, HENRY GOODWIN HOORNBEEK, a citizen of the United States, residing at Springfield, in the county of 5 Hampden and State of Massachusetts, have invented certain new and useful Improvements in Strand-Working Machines, of which the following is a full, clear, concise, and exact description.

- 10 This invention relates to improvements in strand working machines, but more particularly to a holder for material supply cops designed to preserve an even tension on the strand as it is drawn from the cop.
15 An object of this invention is to produce a holder for supply cops for strand working machines, designed so that the material may be fed from the cop under uniform tension.
Another object is to provide a holder for 20 supply cops of such a type that the cops may be readily placed therein and removed therefrom.

To this end a cop holder has been designed in which the supply cop rests on its 25 outer peripheral surface in a support which allows the cop to rotate freely and at the same time is longer than the cop a sufficient amount to allow a free lateral movement thereof.

- 30 In the accompanying drawings,

Fig. 1 is a side view of the mechanism as it appears mounted upon a tinsel serving machine, and

Fig. 2 is a front view of the same, showing just sufficient of the associated machine to illustrate the position of the cop holder.

Referring to the drawings in detail, a frame 10 of a tinsel serving machine of some well known type supports a serving head 11 which serves a strand of tinsel 22 on a central strand 21 in a well known manner. A capstan 30 is driven by the same means as the tinsel serving machine of which it forms a part and by its rotation 45 draws the strand 21 up through the tinsel serving mechanism, through a guide 31 and the tinsel strand is then wound on a take-up spool (not shown) in a well known manner.

- 50 A holder is provided for a supply cop,

consisting of two side plates 40, a supporting member 41, to which the side plates are fastened by rivets 42, and a cradle of polished rods 43 connected to the side plates by suitable means, for instance riveting 70. 55 Tensioning guide discs 50 are carried by an arm 51 which is here integral with the supporting member 41.

In using the cop holder with this form of machine a cop is laid in the cop holder 60 and the strand 21 therefrom is passed between the tensioning guide discs 50 which may be regulated as to the tension they apply by turning a knob 52. The strand is then drawn through the serving head 11, through 65 the guide 31, around the capstan 30 to the take-up spool (not shown). The machine is now ready for operation. On starting the machine the capstan 30 rotates and draws the strand 21 from the cop 20 and 70 up through the machine where it receives the tinsel as it passes through the serving head 11.

The arm 51 carrying the tensioning guide discs 50 is fixed, and owing to the fact that 75 the strand is wound upon the cop diagonally, the tension required to draw the strand from the cop increases greatly with the angle at which the strand leaves the cop. Furthermore, where the center of the cop 80 is held in front of the guide discs during the entire operation the strand is more likely to snag when being drawn from the ends of the cop than it is when being drawn from the center. 85

With the holder embodied in this invention the cop is free to move from end to end as shown. Thus the point at which the strand leaves the cop tends to remain in front of the guide discs during the entire 90 operation, and thereby preserves a uniform tension on the strand at all times.

The force necessary to move the cop laterally is supplied by the strand 21 as it is fed first from one side, then from the other 95 of the cop.

What is claimed is:

A holder for supply cops of strand working machines, comprising a cradle composed of rigidly fixed end pieces and interconnect- 100

ing spaced rods arranged in an arc to support the cop horizontally at spaced points on its peripheral surface, the said arc of the cradle being such as to expose at least half 5 of the periphery of a full cop to be used with said machines, and the cradle being materially longer than said cop whereby the

cop is free to slide longitudinally of the rods.

In witness whereof, I hereunto subscribe 10 my name this sixteenth day of November A. D., 1923.

HENRY GOODWIN HOORNBECK.
